UNITED STATES PATENT OFFICE

THOMAS DOWNHAM NUTTALL, OF BURY, ENGLAND, ASSIGNOR OF ONE-HALF TO BENTLEY & JACKSON LIMITED, OF BURY, ENGLAND, A BRITISH COMPANY

PULP BEATING OR REFINING MACHINE

Application filed April 23, 1930, Serial No. 446,707, and in Great Britain May 21, 1929.

This invention relates to beating or refining machines for the pulp used in paper making, and particularly to machines of the Jordan or similar type in which the grinding pressure between blades upon a revolving cone and a fixed conical casing or housing around said cone is obtained by relative axial adjustments of the said parts.

The object of my present invention is to provide in a ready and efficient manner for the opening out of the conical casing or housing so as to permit of the removal of the revolving cone and the examination or renewal of the blades upon the casing and cone, the arrangement facilitating also the resetting of the casing if and when desired with the part which has formed the upper half thereof, as the lower half so as to equalize the wear of the blades upon the two halves in the known manner.

The invention comprises the division of the conical casing or housing axially into two similar halves or sections with the abutting parts of the two halves diametrically opposite to one another extended radially outwards and supported upon pedestals or brackets forming also retaining guides therefor during adjustment movements.

Referring to the accompanying sheet of explanatory drawings:

Figure 1 is a front elevation of a pulp beating or refining machine constructed in one convenient form in accordance with my invention.

Figure 2 is partly an end elevation and partly a sectional end elevation on the line A B of Figure 3 of the beating or refining machine casing.

Figure 3 is a plan view of the machine casing.

The same reference letters in the different views indicate the same parts.

The casing is divided axially into two halves or sections *a*, *b* adapted to be bolted together and has the abutting parts *c* and *d* of the two halves diametrically opposite to one another and extended radially outwards, the extended parts being carried upon suitable pedestals or brackets *f*, and *g* forming retaining guides therefor, upon which also

they are traversed when adjustment of the casing relatively to the revolving cone within it driven by the motor *h* is being effected. As the division of the casing is on a diametral plane, either portion of the casing can be placed in the top or in the bottom position, and the extended abutting parts be secured in the guides.

My improved construction of casing is neat in appearance and efficient in service. The means for traversing the casing axially may be of any suitable type and do not form parts of the present invention. In Figure 1, a hand wheel *i* is shown, this rotates two worms driving two worm wheels, one of which is shown at *j*. Such wheels act as nuts and are restrained from axial movement so that when rotated they traverse bolts passing therethrough, (one of which is shown at *k*) attached at diametrically opposite points to the end cover *m* of the casing.

What I claim is:—

In pulp beating or refining machines of the type specified, the division of the conical casing or housing axially into top and bottom similar halves or sections having radial flanges at diametrically opposite points for bolting together, fixed pedestals or brackets supporting said casing by said bolted flanges, said pedestals or brackets forming guides for the casing during axial adjustment movements, and means for adjusting the casing along said guides.

In testimony whereof I have signed my name to this specification.

THOMAS DOWNHAM NUTTALL.
